Primary Examiner — Wan Laymon(74) *Attorney, Agent, or Firm* — Dragon Sun Law Firm, P.C.; Jinggao Li, Esq.(57) **CLAIM**

The ornamental design for a mini DLP console projector, as shown and described.

DESCRIPTION

FIG. 1 is a front elevational view of a mini DLP console projector showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a front, left and top perspective view thereof; and, FIG. 8 is a rear, right and top perspective view thereof.

The broken lines in the drawings illustrate portions of the mini DLP console projector which form no part of the claimed design.
